UNITED STATES PATENT OFFICE.

JOHN G. CLEMENS, OF BUFFALO, NEW YORK.

REFILLABLE FUSE-PLUG.

1,174,686.

Specification of Letters Patent.

Patented Mar. 7, 1916.

Application filed May 25, 1915. Serial No. 30,416.

To all whom it may concern:

Be it known that I, JOHN G. CLEMENS, a citizen of the United States, residing at Buffalo, in the county of Erie and State of New York, have invented certain new and useful Improvements in Refillable Fuse-Plugs, of which the following is a specification.

My invention relates to new and useful improvements in fuse plugs and more particularly to fuse plugs of the type in which the fuse may be renewed when burned out or otherwise destroyed, the primary object of my invention being the provision of a renewable fuse plug in which the fuse may be applied without the use of solder, one end of the fuse itself constituting one of the plug contacts and the other end being merely bound in place by the usual contact ferrule of the plug itself.

A still further object of my invention consists in providing for a fuse plug construction such that the plug may be manufactured at substantially the same cost as the plugs now in use and utilized with the usual fuse plug sockets. And a still further object of my invention is the provision of a fuse plug of such a nature that it does not require any particular type or style of fuse or a fuse of unusual construction, the plug being adapted to receive the ordinary strip of fuse metal without any previous shaping or preparing of the metal.

With these and other objects in view, my invention will be more fully described, illustrated in the accompanying drawing, and then specifically pointed out in the claims which are attached to and form a part of this application.

40 In the drawing: Figure 1 is a perspective view of my improved fuse plug; Fig. 2 is a central, longitudinal, sectional view taken through the fuse plug and fuse; Fig. 3 is a transverse sectional view taken on the line 45 3—3 of Fig. 2, looking in the direction of the arrows.

Corresponding and like parts are referred to in the following description and indicated in all the views of the drawing by the same reference characters.

50 My improved fuse plug primarily includes the body portion or plug proper 10, the contact ferrule 11, cap 12 and fuse 13. The body portion or plug 10 may be made of any suitable insulative material, preferably porcelain, and is substantially cylindrical in

shape, being formed with a cylindrical socket 14 opening through the outer or front end of the plug. This plug 10, at its inner or rear end, is reduced slightly and externally threaded to receive the threaded metal sleeve or ferrule 11 which forms one of the plug contacts, as is usually the case. In slightly spaced relation to this reduced portion, the forward end of the plug is formed 60 with an annular threaded shoulder 15 to receive the body portion 16 of the cap 12, this body portion being formed centrally with an opening closed by a plate of isinglass 17 or other suitable transparent material, whereby 65 the condition of the fuse may be readily determined. This annular shoulder 15 also forms a stop shoulder to limit the extent to which the plug may be threaded into its socket. The inner end of the body portion 70 is preferably tapered somewhat to provide a central circular face 18 which, with plugs as now constructed, usually carries a second plug contact.

In my improved fuse plug construction, 80 the closed end of the plug 10 is provided with a slot 19 through which one end of the fuse strip 13 may be passed in order that such end may be bent over against the face 18, as shown at 20, to in itself provide the 85 second contact of the plug. Furthermore, the intermediate portion of the outer face of the plug is formed with a longitudinal channel 21 intersecting certain of the plug threads which engage the threads of the contact ferrule or sleeve 11 and the forward portion of the plug is formed with a recess or slot 22 which communicates between the socket 14 of the plug and the groove or channel 21. As will best be seen by reference to Fig. 2, the free end of the fuse 13 is bent in such a manner as to pass through the slot 22 into the groove 21 and rest across one or more of the threads of the plug in order that it may be clamped in close contact with the ferrule 11 when the latter is threaded upon the plug. 95

Preferably, the plug, at a point beyond the outer end of the groove 21, is formed with a recess 23 into which the end of the 105 fuse may be bent in order that the fuse will not have a tendency to follow the movement of the ferrule when the latter is being turned on or off the plug.

The operation of my improved fuse plug 110 is identical with that of other plugs and need not be described. I will, however, ex-

plain the manner in which the fuse may be renewed. If a fuse burns out in one of my plugs, the cap 12 and ferrule 11 are both removed from the plug and the remains of 5 the fuse may then be readily removed. A suitable length of fuse metal or ribbon is then doubled substantially intermediate its length and one end passed through the slot 22 and the other through the slot 19, the 10 latter end being bent against the closed end of the plug and the former being then clamped in place and in contact with the contact sleeve or ferrule 11 by replacement of such sleeve. The cap 12 is then applied 15 when the plug is again ready for use.

It will of course be understood that although I have illustrated and described my invention in all its details, I do not wish to be limited to such details, as various 20 minor changes, within the scope of the appended claims, may be made at any time without in the slightest degree departing from the spirit of my invention.

Having thus described the invention, what 25 is claimed as new is:

1. A renewable fuse plug including a socketed plug proper having openings in its end and side and having its inner end externally threaded and formed with a channel 30 communicating with the opening through the side of the plug and intersecting certain of the threads, a fuse located in the socket of the plug with one terminal extended through the opening in the end of the plug 35 and bent against such end externally and with its other terminal extending through the opening in the side of the plug and along the channel formed therein and over certain of the uninterrupted threads, and a 40 contact ferrule threaded upon the threaded end of the plug and binding the adjacent terminal of the fuse in place.

2. A renewable fuse plug including a substantially cylindrical socketed plug proper 45 of insulating material having a slot formed in its closed end and at one side of the center of such end and having a recess formed in its side wall opening into a channel formed in the outer face of the plug adjacent its closed end, the closed end portion of 50 the plug being externally threaded with certain of its threads interrupted by the channel, a fuse having one terminal passed through the slot in the closed end of the plug 55 and bent over to engage the central portion of such end and its other terminal passed through the recess and into the slot of the plug, and a contact ferrule threaded upon the plug and clampingly engaging the 60 latter terminal of the fuse.

3. A renewable fuse plug including a socketed plug proper having openings in its end and side and having its inner end externally threaded and formed with a channel communicating with the opening 65 through the side of the plug and intersecting certain of the threads and also formed with a recess beyond the end of the channel, a fuse located in the socket of the plug with one terminal extended through the opening 70 in the end of the plug and bent against such end and with its other terminal extended through the opening in the side of the plug, along the channel formed therein, over certain of the uninterrupted threads and into 75 the recess beyond the channel, and a contact ferrule threaded upon the end of the plug and binding the adjacent terminal of the fuse in place.

4. A renewable fuse plug including a 80 socketed plug proper formed with openings through its side and end, a fuse in the socket having a portion extending through the opening in the end and bent over such end, and a terminal passed through the opening 85 in the side and bent toward the end, the plug being exteriorly threaded and the latter portion of the fuse extending over certain of the threads, and a contact ferrule threaded upon the plug and wedging a portion of the 90 fuse between its threads and the threads of the plug.

5. A renewable fuse plug including a socketed plug proper having one end externally threaded, a fuse bearing at one end 95 over certain of the threads of the plug, and a threaded contact ferrule threaded upon the plug and clamping such end of the fuse against the threads of the plug, the other end of the fuse being passed through openings in the side and end of the plug and bent over the end of the plug.

6. A renewable fuse plug including a socketed plug proper formed with openings in one end and its side, the end of the plug being externally threaded and formed with a recess longitudinally spaced from the opening in the side, a fuse within the plug having one end extending through the opening in the end of the plug and bent over the end of the plug and its other terminal passed through the opening in the side, over certain of the threads and seated in the recess, and a contact ferrule threaded upon the socket and binding the fuse between certain 115 of its threads and certain of the threads of the plug.

In testimony whereof I affix my signature.

JOHN G. CLEMENS. [L.S.]
